UNITED STATES PATENT OFFICE.

JOHN HEBEL, OF HOUSTON, TEXAS.

LUBRICATOR.

1,256,315.

Specification of Letters Patent. Patented Feb. 12, 1918.

Application filed September 1, 1917. Serial No. 189,315.

To all whom it may concern:

Be it known that I, JOHN HEBEL, a citizen of the United States, residing at Houston, in the county of Harris and State of Texas, have invented certain new and useful Improvements in Lubricators; and I do hereby declare the following to be a full, clear, and exact description of the invention, such as will enable others skilled in the art to 10 which it appertains to make and use the same.

The present invention relates to improvements in lubricators, in which an atomizing fluid is mixed with the lubricant, and has 15 for an object to provide an improved mixing chamber having a tortuous discharge where the lubricant and steam, or other atomizing fluid will become thoroughly intermingled.

Another object of the present invention lies in providing the lubricant delivery chamber with an inclined surface on which the oil is dropped, and which surface causes 20 the lubricant to flow in a thin stream down 25 to the mixing chamber, where it is picked up by the incoming atomizing fluid.

In the accompanying drawings forming a part of this application, and in which similar reference symbols indicate corresponding parts in the several views:

Figure 1 is a top plan view of an improved lubricator constructed in accordance with the present invention.

Fig. 2 is a side elevational view thereof; 35 and

Fig. 3 is a vertical sectional view taken on the line 3—3 in Fig. 1.

Referring more particularly to the drawings, the improved lubricator is preferably 40 contained in a block 1 of metal, or other appropriate material, in the upper end of which is provided a lubricant receiver 2, which is kept replenished from a suitable reservoir through a connection 3, which may 45 be under the control of a valve 4.

Centrally beneath the lubricant receiver 2, is a lubricant delivery chamber 5, having therein the sight openings 6, through which the dropping of the oil or other lubricant 50 may be observed as it descends from a nozzle 7, threaded or otherwise removably received in the top of said delivery chamber 5.

The nozzle 7 is preferably so arranged 55 that its upper end is raised above the bottom of the receiver 2, so as to take the oil

from the upper part of the receiver where the same will be in a purer and clearer condition, and without any sediment which will settle to the bottom of said receiver.

From time to time, as it becomes necessary, this sediment may be removed from the receiver 2 by unscrewing a removable plug 8 and inverting the block 1.

The delivery of oil through the nozzle 7 is regulated by a needle valve 9, which is threaded through said plug 8 and seats against the upper end of said nozzle in a manner which will be clear from Fig. 3.

The lubricant drops from the nozzle 7 onto an inclined surface 10, which causes the same to spread out in a thin stream or film, and to flow downwardly toward an opening 11 formed in the lower part of a partition 12, which divides the delivery chamber 5 from the atomizing fluid inlet 13 which is connected to a suitable source.

Below the fluid inlet 13, and adjoining the opening 11, is a mixing chamber 14, wherein the steam or other fluid encounters and becomes thoroughly incorporated with the oil flowing down the inclined surface 10.

A tapering throat 15 forms the bottom of the mixing chamber 14, and communicates with a tortuous or spiral passage 16; such passage 16 connecting with a discharge 17 which is under regulation of a valve 18 for controlling the delivery of the mixed lubricant and fluid to the part to be lubricated.

The oil, or other lubricant enters through the connection 3, and is maintained at a suitable level in the receiver 2 through the control of the valve 4. The delivery of the oil through the nozzle 7 and onto the inclined surface 10, may be nicely regulated through the needle valve 9, and the regulation quickly observed through the sight openings 6.

The steam as it enters the inlet 13 and passes to the mixing chamber 14, will have a siphon-like effect in drawing the oil down the inclined surface 10, where it will be precipitated into the mass of incoming fluid, being thence carried therewith down through the reduced throat 15, and circulating about in the spiral passage 16 will become thoroughly incorporated and produce an excellent lubricant.

It is obvious that those skilled in the art may vary the details of construction and arrangements of parts without departing from

the spirit of my invention, and therefore I do not wish to be limited to such features except as may be required by the claims.

I claim—

- 5 1. A lubricator including a lubricant receiver, a lubricant delivery chamber below said receiver, a sloping surface in said delivery chamber, a nozzle establishing communication between said receiver and chamber and adapted to drop the lubricant vertically upon said sloping surface whereby to cause the same to spread out in a thin film, a valve for controlling issuance of the lubricant through said nozzle, an atomizing fluid inlet, a mixing chamber in communication with said atomizing fluid inlet and lubricant delivery chamber and being located at the lower end of said sloping surface, the incoming atomizing fluid adapted to pick 10 up the lubricant as it is delivered in said film to the mixing chamber, and a discharge from the mixing chamber, substantially as described.
- 15 2. A lubricator including a mixing chamber, an atomizing fluid inlet in communication with said mixing chamber, a lubricant delivery chamber, a sloping surface in said delivery chamber inclining toward said mixing chamber, a lubricant receiver, valve controlled means for causing the lubricant to issue drop by drop from said receiver to the sloping surface in said delivery chamber whereby said lubricant will be spread out in a film-like sheet, a spiral passage leading 20 from the said mixing chamber and adapted to subject the atomizing fluid and liquid to a stirring motion, and a discharge for said lubricator leading from said passage, substantially as described.
- 25 30 35 40 3. A lubricator composed of a solid metallic block having its upper part hollowed out to provide a lubricant receiver, a lubri-

cant delivery chamber formed in said block below the receiver and having a sloping surface, sight glasses in said delivery chamber, 45 a nozzle establishing communication between said receiver and delivery chamber and adapted to pass the lubricant drop by drop to said sloping surface whereby the same will be caused to spread in a thin film, 50 an atomizing fluid inlet in said block, a partition separating said inlet from said delivery chamber and having an opening therein at the lower end of said sloping surface, a mixing chamber in said block adjoining 55 said opening and adapted to receive the lubricant as it flows down said sloping surface, a tapering throat forming the base of said mixing chamber and adapted to bring the atomizing fluid and lubricant into close 60 mixture, and a tortuous passage leading from said tapering throat, substantially as described.

4. A lubricator including a block having a valve-controlled lubricant receiver in its 65 upper end, a nozzle in said receiver with its upper end elevated above the bottom of said receiver, a removable plug to afford access to said receiver, a valve regulating flow through said nozzle, a delivery chamber having sight glasses below said receiver and provided with an inclined surface onto which the lubricant is dropped from said nozzle, an atomizing fluid inlet, a partition separating said inlet and chamber and having an opening at the lower end of said inclined surface, a mixing chamber adjoining said opening, a tapering throat at the base of said mixing chamber, a tortuous passage leading 70 from said throat, and a discharge 75 connecting with said throat, substantially as described.

In testimony whereof, I affix my signature.
JNO. HEBEL.
